AUTOMATIC SWITCH FOR USE IN TELEPHONE SYSTEMS

Cecil Robert Woodland and John Henry Ellis,
Liverpool, England, assignors to Associated
Telephone and Telegraph Company, Chicago,
Ill., a corporation of Delaware

Application December 24, 1931, Serial No. 583,038,
and in Great Britain January 2, 1931

14 Claims. (Cl. 179—27.52)

The present invention relates to improvements in automatic switches of the type used in telephone or like systems and is more particularly concerned with step-by-step switches arranged for movement in two directions, for instance, vertical and rotary. The object of the invention is to provide an improved switch of this type which is extremely compact, rapid in operation and easy to maintain, while at the same time offering additional facilities with less apparatus than hitherto considered necessary.

According to one feature of the invention, the vertical and rotary operating members are arranged as separate units so that while the vertical member may move in a vertical direction independently of the rotary member, the two are arranged to rotate together by means of a slot and pin coupling arrangement.

According to another feature of the invention, the operating pawls for both the vertical and rotary movements together with various adjusting screws for the magnet coils and the like are accessible from the front of the switch so that all adjustments may be made without the necessity of removing the switch from its mounted position.

According to a further feature of the invention the switch shaft is arranged for rotation in one direction only so that a full cycle is always made to effect the release of the shaft to the normal position.

According to a still further feature of the invention, so-called off-normal springs which are actuated when the switch shaft is out of its normal position, are arranged to be fully operated by a vertical movement of the shaft and subsequently fully restored to normal by a rotary movement of the shaft. Such an arrangement, therefore, permits the reliable operation of a large number of spring sets independently of the weight of the shaft.

The invention will be better understood from the following description of one method of carrying it into effect which should be taken in conjunction with the accompanying drawings comprising Figs. 1 to 8. Fig. 1 shows a left-hand side view of the switch in part section, Fig. 2 shows a front view of the switch, Fig. 3 shows a right-hand side view of the switch illustrating more clearly the vertical operating mechanism, Fig. 4 shows a plan view of the bank and cordless wiper assembly, Fig. 5 shows a plan view in part section illustrating further details of the vertical operating mechanism together with the means for operating so-called off-normal springs and

normal post springs, Fig. 6 shows a further plan view in part section illustrating the rotary operating mechanism, Fig. 7 shows a detailed perspective view of the means for operating the off-normal springs in two stages, while Fig. 8 is a rear view of the switch homing the magnets in position with their associated armature restoring springs.

Referring now particularly to Figs. 1 and 5 it will be seen that the frame casting to which the various components are mounted comprises a substantially rectangular box 10 provided at its upper and lower ends respectively with horizontal projecting flanges 11 and 12 between which the operating mechanism for the switch is supported. Down the two sides of the casting 10 are moulded platforms such as 13 which are secured the various spring assemblies shown in full in Fig. 2. It will be seen from the drawings that spring sets similar in shape to those employed on the relays have been made use of almost universally for the special purpose spring sets.

Referring now particularly to Fig. 1 it will be seen that the rotary and vertical operating hubs as already mentioned are arranged as separate units. The rotary hub 14 is of cylindrical form carrying a complete circle of ratchet teeth 9 around an extended flange at its upper closed end and is free to rotate on the vertical guide pillar 15. In order that the assembly shall be quite rigid and free from whip a large bearing bush is formed at the upper end of the cylinder while the vertical guide pillar is riveted into a washer 16 of large diameter which is held in position by a single fixing screw 17. The cylindrical rotary hub is supported in position on the vertical guide pillar by means of a split ring 18 which is sprung over the end of the pillar and drops into a convenient groove thereon. The vertical operating hub 19 shown immediately below the rotary hub is provided with circular ratchet teeth of substantially conventional form but the hub is hollowed out to the point 20 to accommodate the vertical guide pillar 15 which serves as a bearing support during the vertical movement of the hub.

In order that both hubs may move as a single unit insofar as the rotary motion is concerned the vertical hub is provided at its upper end with a pin 21 which extends into a long slot 8 cut vertically in the face of the cylindrical rotary hub and shown more clearly in Fig. 2. During the vertical movement of the shaft therefore, the pin will ride freely up the slot while subsequently upon the energization of the rotary magnet the drive will be transmitted to the shaft by means of the pin.

Conveniently the pin may take the form of an extended tongue on a washer-shaped member which may be secured to the end of the vertical hub by riveting it in position, while the hole in the 5 washer which is concentric with the slightly less in diameter hole in the vertical operating hub may be made to serve as a bearing surface on the vertical guide pillar.

Considering now particularly the vertical 10 movement mechanism, it will be seen from Fig. 3 that the operating magnet 22 is mounted inside the box casting while its armature 23 which is pivoted at the point 31 is located at the front of the casting and is provided with an extended arm 15 24 which is bent at its end into the form of a fork so that the vertical operating pawl 25 may be pivoted therein, in which position it is readily accessible for adjustment purposes. In the views Figs. 2 and 3 the armature and pawl are shown 20 in operative engagement with the vertical hub, and it should be explained that the pawl is provided with a spring which may be conveniently supported on the pivot pin, and is arranged to exert pressure on the pawl in such direction as 25 to cause it to engage with the vertical hub. In order, however, that the pawl shall be clear of the hub when the armature is in its normal position, it is provided with an extended arm 26 shown in Figs. 2 and 5 arranged to engage with 30 the adjustable stop 27, comprising a bolt and locking nut which may be adjusted as regards its height to produce the necessary tilting movement to lift the pawl clear of the hub when the normal position is reached. A further adjustment 35 for the armature as regards its stroke is provided in the shape of the adjusting screw 28 shown immediately below the forked portion of the extended arm in Figs. 2 and 3.

Considering now the energization of the vertical magnet 22 during the operation of the switch, it will be appreciated from Fig. 3 that the armature on being attracted by the magnet will cause the extended arm of the pawl by this means 40 relieved, the latter will under spring pressure enter a tooth on the vertical hub which is then lifted carrying with it the shaft and wipers until the pawl locks against the upper pawl stop 29. The upper pawl stop 29 is also slidably adjustable 45 and may be locked in position by means of the bolt 30 so as to regulate the stroke of the armature and consequently the lifting motion of the shaft and wipers. In this manner, therefore, the shaft and wipers are raised upon the operation of 50 the armature which as will be seen from reference to the rear view of the magnets shown in Fig. 8, is made against the action of a flat restoring spring 31, provided with two arms so that it may serve the dual purpose of restoring both the 55 vertical and rotary magnet armatures. In order that the spring may be readily adjustable as regards its tension each of the armatures is provided with an adjustment screw which projects against the end of the spring and is accessible 60 from the front of the switch so that adjustment 65 may be carried out without removing it from the mounting shelf.

Referring again to Fig. 1 it will be seen that the vertical hub is provided at its lower end 70 with a conical shaped cam 32 arranged to cooperate with a projection on a pivoted lever 33 which actuates the off-normal spring assembly shown more clearly in Figs. 5 and 7. In order that the action of this lever shall be more clearly 75 understood a separate perspective view has been

provided in Fig. 7 from which it will be seen when the shaft is lifted the cam will clear the operating lever 33 so that this latter will then be moved by the pressure of the spring set into its operated position against a projection on the casting in which position the contacts shown will be opened. As already mentioned the restoration of the off-normal spring set is performed in two stages and the manner in which this is effected will be fully described later.

Vertical magnet interrupter springs may be fitted when required on the lower right-hand side of the casting in the position indicated by 34, Fig. 2, and are operated by a ball and plunger arrangement. Conveniently in the construction shown the ball 35 is housed in a cavity formed in the casting and is rendered captive therein by ring punching the sides of its cavity to a slightly smaller diameter than that of the ball so that a portion of its circumference may extend therefrom to be in line with the operating path of the vertical magnet armature. Consequently when the armature is energized, its right-hand edge will ride over the surface of the ball so as to cause the latter to recede into the cavity thereby operating the plunger 36, which is provided at its end with an insulated buffer to effect the operation of the vertical magnet interrupter spring set 34.

At each vertical step the vertical hub and shaft 105, are held in position by a spring-loaded detent pin 37 shown in Fig. 2 which is slidably supported between the arms of a U-shaped bracket 38 which is, in turn, secured to a smaller projecting flange located in a mid position on the 110 front face of the casting. The contact face of the pin is cut in such manner as to correspond to the angle of the ratchet teeth on the vertical hub and in order that its movement shall be restricted within the desired limits a further 115 guide pin 39 is set transversely through the detent pin and is provided with an extended end which rides in a slot cut in the base of the U-shaped supporting member. Conveniently also the guide pin is arranged to hold in position a 120 washer 40 which forms a compression plate for the helical spring 41.

Two sets of normal post springs are provided in the position indicated by 42 and 43 in Fig. 2 and are operated by separate levers actuated from 125 a ring cam 44 mounted on the vertical hub. The mounting of the levers designated 45 and 46 is shown more clearly in Figs. 2 and 5 from which it will be seen that they are pivoted one behind the other to an extended bracket secured to the 130 casting and are provided with operating faces equal in length to the maximum vertical movement of the switch shaft. Into each of these operating faces are drilled vertically 10 holes into which operating studs, such as 47 and 48, may 135 be secured in positions depending upon the level or levels at which it is desired to effect operation of the spring sets. The operating cam is shown more clearly in Fig. 1 from which it will be appreciated as the shaft is lifted the ring 140 will engage with the studs in the desired positions and effect a rocking movement of the levers to operate the spring sets. In order to reduce friction when the shaft is subsequently rotated it is arranged that the operating ring 44 is 145 mounted loose on the shaft so that it is free to rotate independently.

The rotary stepping of the shaft is carried out by a single coil and magnet similar to that used for the vertical stepping which is also 150

mounted inside the box casting above the vertical magnet in the position indicated by 49 in Fig. 6. Both magnets are secured in position by clamping screws which extend through slotted 5 holes in the casting and these may be seen more clearly in respect of the vertical magnet mounting shown in Fig. 5 in which fixing screws are designated 50 and 51. Moreover the magnet fixing bracket 52 is arranged to slide between ribs 10 provided on the inside face of the casting, so that when it becomes necessary to alter the position of the magnet this may be done by slackening off the screws 50 and 51 so that the magnet assembly may slide backwardly or forwardly between the ribs. In order to permit of a comparatively fine adjustment the movement is controlled by a screw similar to the screw 53 shown more clearly in Figs. 2 and 6 associated with the rotary magnet 49. This screw is threaded 15 into the casting and provided with a collar 54 which enters into a slot in the magnet fixing bracket so that when the screw is rotated in either direction a corresponding backwards or forwards movement of the magnet will be secured. 20 Considering now the rotary magnet mechanism shown more clearly in Fig. 6 it will be seen that the operating magnet is provided with an armature 55 also located on the front of the switch which is pivoted at the point 82 and provided with 25 an extended arm 56 carrying a spring-loaded pawl 57 normally arranged to bear against the ratchet teeth 9 which as previously explained are provided in a complete circle around the flange on the cylindrical hub. In the drawings the rotary 30 magnet armature and pawl are shown in their operated position, so that when the magnet is de-energized the armature will restore under pressure of the flat restoring spring 31 and carry with it the rotary hub until the pawl takes up the position indicated by the dotted lines when it becomes 35 locked against the adjustable pawl stop 58. A light holding detent spring 59 which is also adjustable from the front of the switch is incorporated in the rotary mechanism so as to prevent the 40 movement of the shaft in a reverse direction as the pawl 57 is being drawn over the ratchet teeth 9 into its operated position by the energization of the magnet 49. The pawl stop 58 may be slidably 45 adjusted and locked in position by the locking screw 60. In addition to the pawl stop an adjustable armature stop 61 is provided shown more 50 clearly in Fig. 3 and this comprises a bracket carrying a projecting tongue which is secured to the edge of the casting flange 11 through slotted 55 holes so that it may be adjustable as regards its position, and is arranged to contact with the turned up end of the armature lever 62 so as to regulate the releasing stroke. 60 Since with the present construction the usual shaft cup spring has been dispensed with, it is found that the power to operate the shaft is reduced to approximately one half and it is anticipated that this saving combined with the reverse 65 stepping rotary movement will enable a hunting speed comparable with that of a single motion switch to be obtained. At the conclusion of each rotary step the shaft is held in position by the detent pawl spring 59 and as the rotary detent is 70 quite separate and distinct from the vertical detent it is not now necessary to enlarge the size of the vertical ratchet teeth at the point where they contact with the detent pin during the vertical movement. This enlargement of the ratchet teeth has hitherto been considered essential to 75 ensure the reliable operation of the so-called double dog detent during the rotary movement. 80 Rotary magnet interrupter springs may also be fitted if required to the left-hand side of the switch frame in the position indicated by 63 in Fig. 2 and these may be operated by an extended arm 64 on the rotary magnet armature in the manner shown in Fig. 6. Conveniently in the construction shown the rotary interrupter spring assembly is arranged to open contact at the conclusion of the attraction stroke, and in order that the magnet may be reliably energized in a self-interrupted circuit without the possibility of the mechanism failing to function owing to clipped 85 impulses, a certain degree of lost motion is incorporated in the operating mechanism. As will be better appreciated from Fig. 6, this mechanism comprises essentially an insulated buffer 65 slidably mounted to a pin 66 which is riveted into the end of the operating lever, shown in Fig. 6 in its operated position. In the normal position when the magnet is de-energized the buffer is inserted between the spring sets shown so that their turned up ends will drop into the recessed portion on the buffer to allow the electrical contacts 67 to 90 make. On the operation of the magnet the armature will be well advanced in its stroke before the buffer is withdrawn from between the springs into the position shown, since the pin on which it is mounted is of somewhat greater length than the 95 buffer, and will not, therefore, impart the movement to the buffer for an appreciable period after the initial movement of the armature. Similarly upon the de-energization of the magnet the switch shaft will be well advanced in its operating movement before the buffer is again inserted between the spring set to close the electrical contacts. In this manner, therefore, the energizing circuit of the magnet is controlled by the movement of its 100 own armature which incorporates a double-acting 105 delay device to ensure that each movement of operation and release shall be adequately made before the circuit change which terminates the movement is again effected. Alternatively in 110 case the magnet is to be controlled in a circuit 115 which does not necessitate this delayed action device, the interrupter springs may be operated without lost motion by an extension of the rotary magnet armature or alternatively by a ball and plunger arrangement similar to that described in 120 connection with the vertical magnet interrupter 125 springs. 130 Rotary off-normal springs are also secured to the left-hand side of the casting at the point designated 68 in Fig. 2. These springs are normally held operated under strain by a projection 135 69 screwed or moulded on to the cylindrical face of the rotary hub which engages with the spring mounted cranked operating lever 70. As soon as the hub commences its rotary movement the projection will be moved out of line with the operating lever and the spring sets are then operated under tension of their own moving springs, or alternatively by means of a special spring which could be conveniently incorporated 140 in the same assembly. 145 As already mentioned the release of the switch is effected by rotating the shaft and wipers clear of the banks whereupon they fall by gravity and are then moved to the normal position in a manner which will now be described. When the shaft is rotated into its 11th position, so-called cam springs designated 71 shown to the right-hand side of the switch casting in Fig. 2 are operated by a further projection 83 on the cylinder 150

drical portion of the rotary hub, but their operation is without function at this stage since the circuit conditions ruling at the time are indicative of a release condition rather than an all-outlets-busy condition and the necessary distinction between the two will be readily conceivable to those skilled in the art without further description herein. Further rotation of the shaft into the 12th position will effect the operation of further cam springs designated 72 in Fig. 2 and these are arranged to disconnect the rotary magnet circuit. In this position the wipers will be moved clear of the bank contacts and a still further projection 84 on the cylindrical hub more clearly seen in Fig. 2 will engage with the guide pin 39 of the vertical detent 37 thereby moving the latter against the tension of the spring 41 out of engagement with the vertical ratchet teeth so that the shaft and wipers fall by gravity into their vertical normal position. In this position the conical shaped cam 32 at the base of the vertical hub shown in greater detail in Fig. 7 effects the operation of a single set of off-normal springs 73 but does not effect the remainder of the spring assembly since the end of the lever enters the recessed portion 85 of the cam and therefore only a slight movement is produced. The operation of the light off-normal springs 73 again connects up the rotary magnet circuit so that the shaft and wipers are moved a further two rotary steps into their final home position, and by this means the operating lever 33 will be caused to ride out of the recessed portion of the cam on to the external face and this latter movement serves to effect the full operation of the off-normal spring sets. In this manner a large assembly of off-normal springs may be reliably operated irrespective of the weight of the shaft since the major restoring movement is produced from the rotary magnet drive.

The cordless wiper arrangement may be more clearly seen in the plan view, Fig. 4, and comprises the usual wiper arm 74 together with an arc shaped wiper brush 75 both of which may be conveniently pressed out in a single stamping. A contact comb 86 is also provided and is secured to the square sectioned pillar 76 fastened to the base flange of the switch casting. As will be seen from Fig. 2 the contact comb is provided with terminal points such as 77 equal in number to the contact levels and arranged so that the upper and lower arc shaped brushes may establish continuous contact with them during the rotation of the wipers to any set of contacts in the associated level. In the particular example shown it is assumed that the switch is to be used in circumstances where not more than 10 outlets are required for a single rotation of the shaft and wipers and under these conditions it is necessary to provide double-ended wipers and also double feed brushes. In case, however, 20 outlets are required for a single rotation of the switch, single-ended wipers will be used arranged to contact with upper and lower banks successively, so that as one wiper leaves the upper bank the lower wiper will enter the lower bank and in this manner 20 consecutive outlet points are provided for a single rotation of the shaft and wipers. In connection with the wiper and comb arrangement it may be pointed out that the contact arc and the actual wiper arm need not be adjusted relative to each other since with the arrangements contemplated the

wiper arm 74 will not be required to pass over the comb feeds 86 for the contact arc 75.

Considering this feature in detail, when the wipers are rotated into their 12th position the wiper arm will leave the contact bank while at the same instant the contact arc will leave the comb feed. Consequently when the mechanical release action comes into operation the shaft and wiper will drop clear of both the comb and the contact, and when the home position is reached the light off-normal springs will be operated to close the rotary magnet circuit by means of which two further steps will be taken to advance the wipers into their rotary home position. Since, however, the shaft and wipers are fully restored insofar as the vertical release movement is concerned during their final rotary stepping operation it will be clear that the wiper arms will move into their normal position well below the comb feed. This feature is of importance since otherwise if the arrangements were such that the wiper arm was caused to wipe over the comb feeds during each revolution, then very careful aligning would be necessary between the comb feed and the bank contacts so as to ensure that there should be no possibility of the wiper arm fouling the comb during the release operation. It may be mentioned that the elimination of the wiper cord makes possible a saving in the overall height of the switch since it is not now necessary to provide clearance space below the banks for the usual cord loop.

Although not shown in the drawings provision is contemplated of a semi-circular guard plate arranged to be fastened in front of the banks and wipers so as to protect them from damage. Conveniently in one construction this guard may take the form of a metal plate punched out with a very coarse mesh so as to permit minor adjustment to be made therethrough, but at the same time providing adequate protection against accidental damage.

A vertical bank and wiper may also be fitted to the switch on one of the bank mounting pillars as is the general practice at the present time, while a so-called P. B. X. bank arc may be fitted immediately below the normal bank assembly on the same mounting pillars.

Since the switch is now mechanically capable of testing 20 contact points consecutively, the use of the so-called double choice relay generally employed in circuits for switches having more than 10 outlets may now be dispensed with, thereby considerably simplifying the circuit arrangements and necessitating no change in the size of the relay mounting plate. In this connection considering a group selector switch of the well-known construction which requires only four control relays, there is a saving of approximately four inches in the overall height of the switch and a further saving of approximately one inch from back to front.

The use of a separate base plate and felt ring for the prevention of dust trouble is now discontinued and replaced by the flange 12 shown in Fig. 1 which is formed with the casting and provided with a turned over lip all round. The dust cover 78 is of conventional form and is now arranged to fit flush against the sides of the lip formed around the base flange thus obviating trouble which has been experienced hitherto owing to particles of felt fluff produced by the continuous use of the cover becoming lodged between the operating contacts thus preventing the proper

functioning of the switch. In order to follow the general practice of insulating the switch mechanism from the mounting plate and shelf, an insulated beading of generous dimensions 5 is provided around the lower edge of the dust cover at the points where it overlaps the base flange. Conveniently this beading may take the form of a U-shaped strip of insulating material 79 clamped in position by a U-shaped strip of 10 metal 80 of similar dimensions. At the point where the cover contacts with the top of the mounting plate a resilient strip 87 will be provided composed of material which is not productive of fluff during use.

15 We claim:

1. In a switch structure, two wiper sets, means for moving the wiper sets in two directions to associate one set with a cooperative set of fixed contacts, apparatus enabling a part of said means to further move said wiper sets to enable their partial restoration, and means operated consequent to such partial restoration enabling the said part of said means to further move said wiper sets to position the other of said wiper sets in the same relation to the fixed contacts as was the one set prior to the operation of the switch.

2. In a switch mechanism, a shaft, means for elevating said shaft, means for holding said shaft in its elevated position; means for then rotating said shaft variable distances to selectively establish electrical connections; means operated to disable said second means consequent to the subsequent rotations of said shaft an additional distance thereby causing said shaft to drop to its initial level, and means operated consequent to the restoration of said shaft to its initial level to enable said third means to again rotate said shaft an additional distance making the total distance of rotation 180° for each operation and release of the switch.

3. In a switch structure wherein a wiper set is first moved in a primary direction to select one of a plurality of groups fixed contacts and is then moved in a secondary direction to establish a connection with a particular contact of the selected group; the provision of means enabling only a partial restoration of said wiper set to be required to enable the switch to again perform its specified selecting and connecting function.

4. In a switch structure wherein a wiper set is first moved in a primary direction to select one of a plurality of groups of fixed contacts and is then moved in a secondary direction to establish a connection with a particular contact of the selected group; and wherein the restoration in the primary direction is effected as a result of a continuation of the secondary movement; the provision of means enabling the restoration to normal to be brought about by still further secondary movements of the wipers.

5. In a switch mechanism, a supporting member, a shaft having a bearing in said member, means for transmitting endwise movement to said shaft, sets of contact springs arranged on said member, and a plurality of arms pivotally mounted on said member actuated by said shaft during its endwise movement to operate said sets of contact springs.

6. In a switch mechanism of the type in which a set of wipers is caused to move in a primary direction to select one of a number of contact groups and which is then moved in a secondary direction to connect with a set of contacts of

the group selected; mechanism which causes the wipers to move clear of their contacts and restore as regards their primary position; and other mechanism operative, consequent to the specified restoration, to effect the further movement of the wipers in the secondary direction to complete the restoration of the switch.

7. In a switch mechanism wherein a shaft is operated in a primary direction and then in a secondary direction to position its wipers into electrical connection with a specified set of bank contacts; means for initiating and completing the restoration of the switch to normal by subsequent operations of the shaft in a secondary direction.

8. In a switch mechanism wherein a shaft is operated in a primary direction and then in a secondary direction to position its wipers into electrical connection with a specified set of bank contacts; means for holding the shaft against a restoring force tending to move the shaft to normal with respect to its primary movement, means operated consequent to a continued secondary movement to disable said holding means, means operated upon the consequent restoration of the shaft to effect a further limited secondary movement thereof to fully restore the shaft to normal position with respect to both movements.

9. In a switch mechanism wherein a shaft is operated in a primary direction and then in a secondary direction to position its wipers into electrical connection with a specified set of bank contacts; mechanism for restoring the shaft to normal by a further movement thereof in a secondary direction to effect the restoration thereof as regards its primary movement, and means actuated upon such restoration to bring about a further movement of the shaft in a secondary direction to restore the shaft to normal as regards its secondary movement.

10. In a switch mechanism of the character covered by claim 9, characterized in this; that all springs of a set of off normal springs are arranged to be fully operated upon the initial primary movement of the shaft, some of which are restored upon restoration of the shaft as regards its primary movement, and the remainder of which are arranged to be restored upon a completion of the last specified secondary movement.

11. In a switch mechanism, a base having mounted on one side thereof a plurality of relays having circuit controlling springs, the terminal portions of the springs passing through openings in said base, a member also mounted on said base comprising a switch mechanism; and a plurality of circuit controlling springs forming a part of said switch mechanism proper, said springs having their terminal portions passing through openings in said base, thereby enabling all wiring in the various springs of the switch mechanism as well as of the relays to be made on the side of the base opposite to that on which said relays and switch mechanism are mounted.

12. In a switch mechanism wherein a shaft is operated in a primary direction and then in a secondary direction, a set of wipers carried by the shaft having a flat sector-shaped plate integral therewith, and a fixed comb-shaped member to which external connections are made and the teeth of which are adapted to be engaged by said plate.

13. In a switch mechanism wherein a shaft is operated in a primary direction and then in a secondary direction, means for effecting the primary and secondary movements of the shaft com-

prising pawl and ratchet mechanisms in which the ratchet teeth employed in the primary movement are on the shaft and those employed in the secondary movement are on a cylindrical member; the shaft being arranged to slide, during its primary movement, into said member, but being arranged fixed with respect thereto during its secondary movement.

14. In a switch mechanism wherein a shaft is

operated in a primary direction and then in a secondary direction, electromagnets having armatures for operating such mechanism, a pair of interrupter contacts, and lost motion means actuated by one of said magnets to open said contacts at one end of its armature stroke and to again close said contacts at the other end of its stroke. 80
